UNITED STATES PATENT OFFICE

2,203,828

PUMP

Swan E. Larson, Rockford, Ill., assignor to Geo. D. Roper Corporation, Rockford, Ill., a corporation of Illinois

Original application June 8, 1936, Serial No. 84,146. Divided and this application October 29, 1936, Serial No. 108,236

18 Claims. (Cl. 103—175)

This application is a division of my copending application Serial No. 84,146, filed June 8, 1936, which resulted in Patent No. 2,133,708, issued October 18, 1938.

5 This invention relates to a new and improved reciprocating pump, especially designed for use in a pump unit for a domestic water system but, of course, capable of a variety of uses.

The principal object of my invention is to provide a reciprocating pump in which all of the valves are congregated on a single plate disposed preferably in a vertical plane and assembled removably between the body and face plate, whereby to insure the dropping away from the valve seats of any solids which would otherwise prevent closing of the valves, and also permit removal of the entire set of valves at one time for inspection, repair or replacement. The plate carrying the valve is also preferably porcelain enameled to 20 resist corrosion and avoid sticking.

Another object is to provide a reciprocating pump in which the liner for the cylinder is renewable and mounted in a novel manner to facilitate its removal when the face plate is off. Both 25 the valve plate and cylinder liner are easily removable when the face plate has been removed.

Other objects and advantages of the invention will appear in the course of the following description, in which reference is made to the accompanying drawings, wherein—

Figure 1 is a front view of a pump unit embodying the pump of my invention;

Fig. 2 is a central vertical section through the pump on a larger scale;

35 Figs. 3, 4 and 5 are transverse vertical sections on the correspondingly numbered lines of Fig. 2;

Fig. 6 is an edgewise view of the valve plate showing the valves thereon in side elevation;

Fig. 7 is a section through one of the valves, 40 as indicated by the line 7—7 in Fig. 6;

Fig. 8 is a section through an air bleeder taken on the line 8—8 of Fig. 3, and

Fig. 9 is a developed diagrammatic section to illustrate the water circuits in the pump.

45 The same reference numerals are applied to corresponding parts throughout the views.

The reciprocating pump of my invention is illustrated in Figure 1 as forming part of a pump unit, the pump being indicated generally by the 50 reference numeral 10. This pump is operated from a crankshaft, driving gear, and eccentric in the crankshaft housing 11. The latter is cast as an integral part of a frame forming the base 12 for the unit and carrying the storage tank 13 thereon. The body or multi-chambered manifold

14 of the pump forms one end of the base 12. The face plate 15 is also a multi-chambered casting and fastened to the body 14, as by bolts 16, to clamp the valve plate 17 in place therebetween, together with gaskets 18 on the opposite sides thereof. A web 19 connecting the tops of the body 14 and housing 11 is machined flat on top to provide a seat 20 whereon to mount the tank 13 on a gasket 21. In other words, the base 12 provides, in a single casting, the pump 10 at one end and the driving mechanism at 11 in the other end while at the same time affording support for the storage tank 13 on top. The electric motor (not shown) furnishing the power for the driving mechanism in the housing 11 is supported on the 15 opposite side of the housing from that appearing in Fig. 1.

The cylinder 22 for the pump 10 is formed integral with the body 14 at the center thereof, concentric with a stuffing box 23 provided in the 20 back wall of the body, and a removable plug 24 threaded in the front wall of the face plate 15. A sleeve 25 forms a renewable liner for the cylinder 22 and has a slip fit in the cylinder. The liner is externally threaded, as at 26, to receive a 25 flanged threaded collar 27. The latter is received in a central hole 28 in the valve plate 17 and is clamped between the gaskets 18 when the face plate 15 is bolted in place. Thus, the liner 25 can be removed and a new one inserted simply 30 by removing the face plate 15 and, of course, the valve plate 17 is also removable at that time, if desired. In the past, the brass liners were invariably pressed in, and hence it was very difficult to remove the same, and such repair jobs were 35 correspondingly expensive. It was also common practice to have the liners rolled over or belled out at the ends to make them tight, and that, of course, made it so much more difficult to remove the same. A slip-fit cylinder liner clamped 40 in place, as herein disclosed, can be replaced in a small fraction of the time required for the old liners, and a great saving in expense is realized for the user.

29 is the pump piston or plunger which is made 45 up of oppositely facing cup leathers held together by a grommet 30 which is provided with a threaded bore in the rear end and a screw-driver slot in the front end for threadedly securing the piston 29 on the reduced threaded front end of the rod 31. The latter is reciprocable in the stuffing box 23 and extends from the crosshead 11. Obviously, when the plug 24 is removed, the piston 29 is accessible and can be removed with the aid 50 55

of a screw-driver, without removing the face plate 15. Hence, this part which is most subject to wear and most apt to require replacement is most easily accessible.

5 The valve plate 17, shown removed in Fig. 6, and also appearing in Figs. 2, 7 and 9 is, of course, perforated to receive the bolts 16 for fastening the face plate 15 to the body 14. The valve plate 17 is assembled in a vertical plane 10 between the body 14 and face plate 15, so that any sediment that would lodge between the valves and seats if the plate were horizontal, will tend to wash down and leave the valve seats clean. In addition, it has ports therein to register with the ports 32-39 provided in the front wall of the body 14, in addition to holes for the projection therethrough of small air bleed nozzles 40 and 41. There are four valves 42, 43, 44, and 46 on the plate 26 to control the flow of 15 water through the ports 32, 33, 34 and 36, respectively. The advantage in having all of the valves on one removable plate is believed to be obvious. The valves 42-44 are on the rear side 20 of the plate and serve as check valves to prevent outward flow through the ports 32-34, respectively, whereas the valve 46 is on the front side and prevents inward flow through the port 36. The back wall of the face plate 15 has ports 32'-38' registering with the ports 32-38, respectively. A strainer 47 is entered in the port 37' and is carried on a screw plug 48 removable from the face plate. A passage 49 in the face plate communicates at its rear end with the port 39 in the body 14 and at its front end with a 35 valve seat 50 for a combination relief and drain valve 51 provided in a hollow boss 52 on the front of the plate 15. A drain pipe 53 extends from the boss 52 to the sewer or other drain receptacle. A hand operable plug 54 is screwed into the boss 52 and forms a guide for the stem 55 of the valve 51 and an abutment for its spring 56. The plug is arranged to be threaded in a predetermined distance, as indicated in Fig. 2, to compress the spring 56 a predetermined 40 amount to hold the valve 51 seated under such spring pressure that it will open when a predetermined pressure is exceeded in the passage 49, as, for example, in the event the pressure regulator switch for the drive motor fails to function. Now, of course, one may back up the plug 54 sufficiently to unseat the valve 51 and thus use the valve as a drain cock, as, for example, when the pump unit is to be drained for inspection, cleaning, or repair, or in the event the unit 45 is to be left standing out of commission for some time, and is accordingly drained to prevent freezing.

The body 14 has chambers A, B, C, and D provided therein. The front plate has three chambers E, F, and G in one plane, and a fourth chamber H in a forward plane communicating with the chamber G through the port 34'. The chambers B and F communicate directly with the opposite ends of the working cylinder 22, that is, with the opposite ends of the cylinder sleeve or liner 25. The chamber A communicates through the port 57 with the storage tank 13. 58 is the water supply pipe extending to the well or cistern, and communicates with the chamber D in the body 14. 59 is the service pipe extending to the service system, and communicates with the storage tank 13 through a cored 60 passage 60 in the web 19. The circuit for the water can now be traced: The incoming water 65 from pipe 58 enters chamber D, as indicated by 70

the arrow in Fig. 9, and passes through strainer 47 into chamber H and thence through port 34' into chamber G. Now assuming the piston 29 is moving outwardly, water is accordingly drawn into the rear end of the cylinder 22 from chamber B and expelled from the front end into chamber F. The water drawn into the rear end of cylinder 22 enters chamber B past check valve 44 from chamber G, as indicated by the arrow. The water expelled from the front end of cylinder 22 into chamber F flows from chamber F past check valve 43 into chamber A, the check valve 46 seating to prevent back-flow. The water forced into chamber A displaces other water from chamber A into tank 13 through port 57, 15 the check valve 42 seating to prevent outward flow. There is an air dome 61 provided inside the tank 13 in the form of a pipe closed at its upper end and threaded at its lower end in a socket provided therefor in the tank hold-down 20 plate 62, and communicating with the chamber A through the hole 63. This air chamber is to avoid water hammer action and by incorporating it inside the tank greater compactness and better appearance are obtained. The water 25 from port 57 finds its way into the tank through the passage 64 in the hold-down plate. On the return stroke of the piston 29, the water previously drawn in behind the piston is expelled into chamber B and flows through port 38' into 30 chamber E and past check valve 42 into chamber A, as indicated by the arrow, the check valve 44 in this case seating to prevent outward flow from chamber B to chamber G. The water entering chamber A displaces other water there- 35 in, forcing water into tank 13, the check valve 43 in this case seating to prevent leakage from chamber A to chamber F. Water drawn into the front end of cylinder 22 in the return travel of piston 29 is supplied from chamber C past 40 check valve 46 to chamber F, the valve 44 seating to prevent taking water from chamber B, and the valve 43 likewise seating to prevent taking water from chamber A. Obviously, therefore, water is continuously being delivered under 45 pressure from the cylinder 22 into chamber A alternately from opposite ends of the cylinder. It is clear that the strainer 47 catches any solid foreign particles therein, since the water entering chamber H from chamber D has to pass 50 through this strainer. The removal of the strainer by means of the plug 48 for cleaning at intervals keeps the unit operating efficiently at all times. It is also clear how the combination pressure relief and drain valve 51 operates, since 55 it has direct communication with the chamber A, just described, and hence communicates also with the storage tank 13. It should also be clear that the nozzles 40 and 41, being at a high level 60 in the chambers E and F (Fig. 5), will serve to drain the air out of these chambers in the filling of the pump unit with water, and will thereafter bleed off any air that happens to collect in these chambers during the operation of the unit, so that the piston 29 will at no time be air-bound 65 and fail to pump water properly. In passing, attention is called to the plug 65 on the face plate 15, (Fig. 1) the removal of which permits priming the pump by filling the chamber H and communicating chambers G and C through the 70 inclined neck 66.

The valve plate 17, in accordance with my invention, and as clearly illustrated in Fig. 7, is porcelain enameled all over, as indicated by the numeral 67, the enameling extending into all of 75

the ports, as shown. This prevents corrosion and also gives the advantage that the rubber disks 68 used in the valves 42, 43, 44, and 46 will not stick thereto. Each valve comprises in addition to the rubber disk 68 a coiled compression spring 69 to hold the disk seated and a washer 70 to enclose the spring and provide not only a backing for the spring, but a limiting abutment for the valve disk to limit movement thereof away from the plate. A screw 71 passing through the plate 17, spacer 72, and washer 70 receives a nut 13 to complete the assembly and permit easy disassembling for replacement of valve disks and springs when necessary. The surfaces of the plate 26 contacted by the gaskets 18 have the porcelain enamel preferably etched with acid to roughen the same to make better joints with the gaskets and lessen the danger of leakage.

The device appearing at 74 is an automatic float-operated air inlet valve, which in the event the usual water-level float rises past a certain level, thus indicating the need for additional air, opens the valve and allows air to be delivered through the tube 75 to the chamber F, so as to be entrained with the water that is being forced into the chamber A and thence to the tank 13 in the operation of the pump.

It is believed the foregoing description conveys a good understanding of the objects and advantages of my invention. The appended claims have been drawn with a view to covering all legitimate modifications and adaptations.

I claim:

1. In a pump, a housing having chambers provided therein, a chambered plate arranged to be detachably secured on said housing, a single valve plate interposed therebetween and having a plurality of spring-seated valves thereon controlling communication between chambers in the housing and chambered plate, a pump cylinder in said housing communicating at one end with a chamber in said housing and at the other end with a chamber in said chambered plate, a piston reciprocable therein, and means for detachably fastening said chambered plate to said housing so as to detachably secure said valve plate in place therebetween.

2. A pump as set forth in claim 1, including a plug removably mounted in an opening provided in said chambered plate in substantially concentric relation to said cylinder, said opening being larger in diameter than the piston in said cylinder whereby to permit removal therethrough of said piston, said piston being removably secured on a piston rod and adapted to be unfastened therefrom by access through said opening.

3. A pump as set forth in claim 1, wherein said valve plate is porcelain enameled on both sides and the valves engaging the same are rubber faced.

4. A pump as set forth in claim 1, including a cylinder liner sleeve having a slip fit in said cylinder and receiving the piston with a working fit therein, said sleeve being removable and adapted for replacement, and an annular flanged collar fixed on said sleeve adjacent the end of said cylinder and intermediate the ends of said sleeve, the flange being parallel with the valve plate and arranged to be clamped between the chambered plate and housing when the former is secured to the latter.

5. A pump as set forth in claim 1, including a cylinder liner sleeve having a slip fit in said cylinder and receiving the piston with a working fit therein, said sleeve being removable and

adapted for replacement, an annular flanged collar fixed on said sleeve adjacent the end of said cylinder and intermediate the ends of said sleeve, the valve plate having an opening provided therein to receive said flange therein in the plane of said plate, and gaskets abutting both faces of said plate and flange and compressed between the chambered plate and housing in the fastening of the former to the latter.

6. In a reciprocating pump, a main body having an elongated cylinder bore provided therein, a removable head plate for said body, said body and plate having chambers provided therein communicating with opposite ends of said bore, an externally threaded cylinder liner sleeve having a slip fit in said bore for removable entry therein, a piston reciprocable therein, and an internally threaded annularly flanged collar detachably threaded on said sleeve adjacent the outer end of said bore and intermediate the ends of said sleeve, the flange of said collar being parallel to the joint between the body and plate and arranged to be clamped between said parts in the fastening of said plate to said body.

7. In a pump, a chambered body having a substantially centrally located cylinder therein on a horizontal axis, a piston reciprocable therein, said body also having a substantially vertical side face, a valve plate disposed in a vertical plane in front of said face, a chambered face plate on the opposite side of said plate from the body and arranged to be secured to the latter so as to clamp the valve plate therebetween, gasket means between the body and valve plate and between the valve plate and face plate compressed to prevent leakage when the face plate is secured to the body, and valves on said valve plate controlling communication through holes provided in the plate between the chambers in the body and face plate, all of said valves being disposed like the valve plate in a vertical plane and arranged to engage valve seats provided on said plate, whereby to permit escape by gravity of foreign matter from between the valve plate and valves in the opening and closing of said valves.

8. As an article of manufacture, a renewable cylinder liner for the cylinder of a reciprocating pump comprising a tubular lining member externally threaded for a portion of the length thereof, and a flanged ring internally threaded and mounted on the threaded portion of the liner, the flange of the ring being adapted to serve as a retaining means in fastening the liner in place in the cylinder.

9. A valve and valve seat structure of the character described comprising, in combination, a thin flat sheet metal plate perforated to provide a screw hole and one or more arcuate ports in substantially concentric relation with the screw hole, one face of the plate providing a valve seat surface annularly with respect to the arcuate ports, a valve disk providing a flat face on one side thereof for fluid-tight engagement with the valve seat surface covering the aforesaid arcuate ports, a screw entered through the screw hole from the opposite face of the plate and through a center opening provided in said disk, a spacer sleeve entered freely in the center hole in the disk and abutting the plate on the same side therewith and having said screw extending therethrough, a washer mounted on the projecting end of said screw and abutting the outer end of the spacer, and a coiled compression spring surrounding the spacer and acting between the washer and valve disk to hold the valve disk nor-

mally seated on the plate, said plate being porcelain enameled on both sides and in the ports, and said valve disk being rubber faced for sealing engagement with said plate.

- 5 10. A valve and valve seat structure of the character described comprising, in combination, a thin flat sheet metal plate perforated at a plurality of points to provide at each point a screw hole and one or more arcuate ports in substantially concentric relation with the screw hole, both faces of the plate providing valve seat surfaces annularly with respect to the arcuate ports, valve disks for cooperation with the valve seat surfaces, one at each screw hole, a screw entered 10 through each screw hole from the opposite side of the plate with relation to its associated valve disk and extending through a center hole provided therein, a spacer sleeve entered freely in the center hole in each disk and abutting the 15 plate on the same side therewith and having the associated screw extending therethrough, a washer mounted on the projecting end of each screw and abutting the outer end of the associated spacer, and a coiled compression spring 20 surrounding each spacer and acting between the associated washer and valve disk to hold the valve disk normally seated on the plate, said plate being porcelain enameled on both sides and in the ports, and said valve disks being rubber faced 25 for sealing engagement with said plate.

11. In a pump, a housing having chambers provided therein, a chambered plate arranged to be detachably secured on said housing, valve plate means interposed therebetween having a plurality of spring seated valves thereon controlling communication between chambers in the housing and chambered plate, said valve plate means providing a sheet metal wall between each pair of communicating chambers having one or 35 more ports provided therein through which the communication is established and the wall also providing directly thereon valve seat surfaces for engagement by the valves so as to close the ports, a pump cylinder in said housing communicating 40 at one end with a chamber in said housing and at the other end with a chamber in said chambered plate, a piston reciprocable in said cylinder, and means for detachably securing the chambered plate to the housing with the valve 45 plate means in place therebetween.

- 50 12. A pump as set forth in claim 11, wherein the sheet metal wall between each pair of communicating chambers is porcelain enameled on both sides and the valve engaging the same is rubbed faced.

- 55 13. In a pump unit, comprising a reciprocating multi-chambered pump housing and an operating crankshaft housing, pump mechanism in the first housing operatively connected with a crankshaft in the second housing, said mechanism including a working piston reciprocable horizontally in a cylinder in the first housing, and a piston rod extending thereto from the second housing and operatively connected therewith, a removable 60 cylinder liner for the cylinder slidably removable therefrom from the front of said first housing, a separate valve plate carrying valves thereon and removably mounted on the front of the first housing, and a chambered face plate removably secured to said housing and holding said liner and valve plate in place, the valves in said plate controlling the flow of fluid between the chambers in the first housing and face plate induced by the movement of the piston in said cylinder.

- 70 14. In a pump unit, comprising a reciprocating

multi-chambered pump housing and an operating crankshaft housing, pump mechanism in the first housing operatively connected with a crankshaft in the second housing, said mechanism including a working piston reciprocable horizontally in a cylinder in the first housing, a piston rod extending thereto from the second housing and having a threaded end, and a threaded member to fit said threaded end serving to fasten the piston thereon detachably, a valve plate carrying 10 valves thereon and removably mounted on the front of the first housing, a chambered face plate removably secured to said housing and serving to hold said valve plate in place, the valves in said plate controlling the flow of fluid between 15 the chambers in the first housing and face plate induced by the movement of the piston in said cylinder, and a plug removably received in an opening provided in said face plate in substantially coaxial alignment with said piston and cylinder and of larger diameter than said piston, said plug when removed permitting access to the threaded member and removal of the piston independently of removal of the face plate.

15. In a pump unit, comprising a reciprocating 25 multi-chambered pump housing and an operating crankshaft housing, pump mechanism in the first housing operatively connected with a crankshaft in the second housing, said mechanism including a working piston reciprocable horizontally in a 30 cylinder in the first housing, a piston rod extending thereto from the second housing and having a threaded end, and a threaded member to fit said threaded end serving to fasten the piston thereon detachably, a valve plate carrying 35 valves thereon and removably mounted on the front of the first housing, a renewable cylinder liner slidably removable from said cylinder, a chambered face plate removably secured to said housing and serving to hold said valve plate and liner in place, the valves in said plate controlling the flow of fluid between the chambers in the first housing and face plate induced by the movement of the piston in said cylinder, and a plug removably received in an opening provided in said 40 face plate in substantially coaxial alignment with said piston and cylinder and of larger diameter than said piston, said plug when removed permitting access to the threaded member and removal of the piston independently of removal 45 of the face plate.

16. In a pump unit comprising a reciprocating pump housing and an operating crankshaft housing, pump mechanism in the first housing operating in connection with the crankshaft in the 55 second housing, said mechanism including a working piston reciprocable horizontally in a cylinder in the first housing, the piston comprising opposed cup leathers, a piston rod extending thereto from the second housing and having a 60 threaded end, and a threaded member at the center of the piston headed at one end to retain one of said cup leathers and swaged at the other end to retain the other cup leather, the threaded member fitting the threaded end of said rod to 65 fasten the piston thereon detachably, and said first housing having a removable plug closing an opening provided in the outer wall thereof substantially coaxially aligned therewith and of larger diameter than said piston, the removal of 70 which plug affords access to said threaded member to permit removal of the piston.

17. A pump as set forth in claim 1, including a plug removably mounted in an opening provided in said chambered plate in substantially 75

concentric relation to said cylinder, said opening being larger in diameter than the piston in said cylinder whereby to permit removal therethrough of said piston, said piston having a central fastening member thereon detachably threaded on the end of the piston rod and adapted to be unthreaded therefrom by access through said opening.

18. In a pump, a chambered body having a substantially centrally located cylinder therein in coaxial relation to and projecting from the body, a piston reciprocable therein, said body also having a flat outside face, a sheet metal valve plate disposed in a plane in front of said face having a central opening to receive the projecting portion of the cylinder, a chambered face plate on the opposite side of said sheet metal

valve plate from the body and arranged to be secured to the latter so as to clamp said sheet metal plate therebetween, gasket means between the body and sheet metal plate and between the sheet metal plate and face plate compressed to prevent leakage when the face plate is secured to the body, said sheet metal plate having openings provided therein in circumferentially spaced relation around the aforesaid cylinder to establish communication between chambers in the body and chambers in the face plate, the aforesaid cylinder having communication at opposite ends with certain of said chambers, and valves mounted on said sheet metal plate arranged to cover and uncover said openings in the reciprocation of the aforesaid piston.

SWAN E. LARSON.
